DESIGN FOR A CASING FOR A BREAD TOASTER

Joseph Pavelka, Jr., and Victor Cornejo, St.
Louis, Mo., assignors to Joseph Pavelka, St.
Louis, Mo.

Application December 7, 1938, Serial No. 81,616

Term of patent 7 years

To all whom it may concern:

Be it known that we, Joseph Pavelka, Jr., and Victor Cornejo, citizens of the United States, residing at St. Louis, Missouri, have invented a new, original, and ornamental Design for a Casing for a Bread Toaster, of which the following is a specification, reference being had to the accompanying drawing, forming part thereof.

Figure 1 is a top plan view of the casing for a bread toaster, showing our design;

Figure 2 is a side elevational view; and
Figure 3 is an end elevational view thereof.

We claim:

The ornamental design for a casing for a bread toaster, substantially as shown.

JOSEPH PAVELKA, JR.
VICTOR CORNEJO.
